(57) **CLAIM**

The ornamental design for a bluetooth speaker, as shown and described.

DESCRIPTION

FIG. 1 is a top, front, right perspective view of a bluetooth speaker, showing my design.

FIG. 2 is a bottom, rear, left perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of a circle labeled 9 in FIG. 2 of the bluetooth speaker.

The evenly spaced broken lines in the drawings illustrate portions of a bluetooth speaker which form no part of the claimed design.

The dot-dot-dash broken lines encircling portions of the claimed design in FIG. 2 that are illustrated in enlargements in FIG. 9, respectively, form no part of the claimed design.
